UNITED STATES PATENT OFFICE.

CHARLES G. HAMPSON, OF NEW YORK, N. Y.

MACHINE FOR STIPPLING.

Application filed June 13, 1921. Serial No. 477,009.

To all whom it may concern:

Be it known that I, CHARLES G. HAMPSON, a citizen of the United States, and resident of New York City, in the county of New York and State of New York, have invented certain new and useful Improvements in Machines for Stippling, of which the following is a specification.

The invention relates to an improved 10 machine for stippling fabrics.

The word "fabric" used in this specification is not only intended to cover paper, cloth, awning materials, ceiling canvas, and like flexible material usually stipple, but is

15 used in a more generic sense to cover any material to which the pre-treated surface of which the method disclosed is applicable.

The primary object of the present disclosure is to provide an improved form of machine for stippling stippled surface by a simple rolling operation and the incidental elimination of the objections inherent in the old methods of hammering or tapping the surface under treatment with a bristle 25 brush form of implement.

Another object of the present disclosure is to provide a simple form of machine by means of which the method can be practiced economically and at a speed to take care 30 of fabrics fed thereto at high speed and to provide a simple form of adjustment by means of which the intensity of engagement between the stippling rollers and the coated surface can be regulated to that nicety which 35 will give the desired effects and at the same time compensate for any wear on the rollers during their prolonged operation.

The present disclosure features another 40 use for rollers of the type under discussion. It is found that the soft sponge rollers herein disclosed can carry and discharge the coating material used in the stippling method herein described.

Accordingly another object of the invention 45 is to provide an improved means for applying coating or coloring material to a surface so that the material will be spread over the surface, smoothly, uniformly and evenly and without leaving brush marks 50 or other evidence of the coating applying instrumentality.

Still another object of the invention is to provide a color applying or coating af-

fecting tool which can be readily cleaned with a minimum loss of the color material. 55

Various other objects and advantages of the invention will be in part obvious from an inspection of the accompanying drawings and in part will be more fully set forth in the following particular description 60 of one form of mechanism embodying my invention, and the invention also consists in certain new and novel features of construction and combination of parts hereinafter set forth and claimed. 65

Referring to the accompanying drawings:

Figure 1 is a view in side elevation of a preferred embodiment of a machine showing one means for practicing the method 70 featured in this disclosure and illustrating a preferred embodiment of the physical aspects of the disclosure, parts being broken away to show structure in rear of the broken away parts; 75

Figure 2 is a vertical sectional view taken on the broken line 2—2 of Figure 3; and

Figure 3 is a plan view looking down upon the disclosure in Figure 1 and with one of the rollers broken away in a horizontal plane. 80

It will be understood in general that the device resembles the usual color applying machine, except for the substitution of soft rubber sponge-faced rollers in place of the 85 usual hard, smooth-faced rubber rollers.

In the drawings there is shown an endless belt 10, preferably in the form of a thick rubber blanket passed about end drums, one of which is shown at 11, and one of which 90 is power driven so as to drive the belt which carries the fabric to be stippled and there-through drives the several rollers constituting the main feature of this disclosure.

At the receiving end of the belt there is 95 provided a frame 12 in which the drum 11 is journaled and on which frame is positioned a pair of upstanding bracket guiding frames 13 and 14 positioned on opposite sides of the belt as shown more particularly 100 in Figure 3. The construction of the frames 13 and 14 is similar so that the description of one side of the belt will correspond in general with the description of the construction on the opposite side. The bracket guiding frames 13 each include a pair of up- 105

standing posts 15 and 16 on which are slidably mounted a longitudinally extending bracket 17. This bracket includes a casting and a central box-like portion 18 between the posts 15 and 16 and a pair of oppositely extending overhanging arms 19 and 20. The brackets are raised simultaneously by means of lifting cams 21 carried on a transversely extending shaft 22 and in operative engagement with rollers 23 depending from the underside of the central portion 18. The shaft 22 is provided at one end with a crank handle 24. From the construction shown in Figure 1 it is understood that the lowering of the crank arm from the position shown in this figure, will tend to raise the bracket against the resistance of depressing springs 25 positioned on the posts 15 and 16 and bearing down on top of the brackets.

A stippling roller 25' mounted upon a shaft 26 is journaled at opposite ends in the central portion 18 of the two brackets. To provide for vertical adjustment of opposite ends of the shaft 26 these ends are each supported in a vertically adjustable saddle 27 which includes a nut 28 movable vertically on a screw 29 in turn controlled by a hand wheel 30 extending above the central portion 18. It is a feature of this disclosure to minimize resistance to rotary movement of the rollers and for this reason the shaft 26 is shown mounted in anti-friction bearings 31. In order to permit the ready demounting of the shaft, the opposite ends are shown located in bearings which can be readily removed from the saddle and which are locked in place by means of a keeper 32.

Positioned between the stippling roller 25' and the receiving end of the belt is a color applying roller 33 which engages the fabric on the belt in vertical alignment with the belt drum 11. In operation the roller 33 is adjusted so as to be in relatively firm bearing engagement against the fabric to be coated. Color is applied to the roller 33 by means of a color roller 34 working in a color containing box 35 of conventional form. The roller 33 is mounted upon a shaft 36 opposite ends of which are mounted for vertical movement in a manner slightly different from the form described in connection with the mounting of the stippling roller shaft 26. Referring to the form of this modified bearing at the right hand side of Figure 2 it is noted that the shaft is rotatably mounted in a bearing block 36' which has a nut 37 working on the screw 38 in turn controlled by the hand wheel 39. The nut 37 is held against rotary movement by means of the pin 40 engaging in a longitudinally extending slot 41 formed in the nut.

A stipple modifying roller 42 is journaled in the opposed bracket arms 19 in a manner similar to the description of the mounting

for the color applying roller 33. It is to be understood that the roller 42 is in relatively light bearing engagement with the fabric on the belt and acts to modify or smooth out the stippled effect caused by the engagement with the coated surface of the primary stippling roller 25'.

The machine as thus described is used where a straight, uniform stipple is desired but it is within the scope of the present disclosure to combine the stipple with other effects and for this purpose the stippling roller 25', as shown in Figure 3, slightly modified so as to show an insert 43 of felt designed to apply to the coated fabric a solid color of any desired design as is usual in cloth printing operations.

It will be understood that the several rollers are of the same general design and each includes a central cylindrical core 44 preferably of wood on which is stretched or glued, a relatively thick layer, usually about two inches of an ordinary black sheet rubber sponge. The character of sponge selected, that is, its resiliency, porosity and composition will depend upon the character of the stippled effect desired. In preparing the rollers it is usual to mount the flexible, porous peripheral face of the sponge like work face in position on the core and then buff the work face so as to bring it into cylindrical form, in so far as this is practically possible.

In operation, and assuming that the parts have been properly adjusted, a strip of fabric, such as wall paper or awning cloth, is fed to the receiving end of the belt and the machine is started in operation by causing the belt to move. The fabric is drawn in between the belt and color applying roller and takes up a uniform, well spread layer of color from the roller 33. Rollers of this character have been found to be more efficient than the usual hair brush roller, in that the color is spread over the engaged surface more evenly; there is less loss of color in the brush and, accordingly the brush may be more readily cleaned at the termination of the coloring operation. It is further suggested that where more than one color is to be applied a multiplicity of color rollers may be utilized to contact with the fabric, one after the other, by obvious modifications of the machine disclosed. As the coating passes under the stippling roller 25' it is stippled or mottled with what may be called a rough effect, that is, in which the contrast in shades is more intense than in the finished product after it has passed the modifying roller 42. As the stippled surface passes beneath the modifying roller 42 the relatively rough stipple is toned down so that the contrasts are less vivid and there is produced an extremely pleasing and uniform

type of stipple or mottle effect. It is of course obvious that the stippled fabric may pass beneath even another roller to further modify the stipple and it is assumed that 5 the passing of the fabric under a sufficient number of rollers will continue to tone down the contrasts and so modify the stipple as to give it practically a flat effect.

The effect produced can be modified materially by the adjustment of the stippling rollers with reference to the fabric under treatment. In order to maintain uniformity of effect it is obvious that the rollers must be adjusted to take up for wear.

15 Again care must be exercised to create such an intensity of engagement between the coated surface and the several stippling rollers. While a relatively light contact is featured, the bearing must be sufficient to 20 maintain a positive contact and on the other hand there must not be such a high pressure as will cause the work surface of the rollers to lose its sponge-like characteristics.

25 While I have shown and described, and have pointed out in the annexed claims, certain novel features of my invention, it will be understood that various omissions, substitutions and changes in the form and 30 details of the device illustrated and in its operation may be made by those skilled in the art without departing from the spirit of the invention.

Having thus described my invention, I 35 claim:-

1. In a stippling machine, the combination with a belt for carrying the fabric to be stippled, a stippling roller mounted for rotary movement and with its axis across 40 the line of movement of the belt, said roller being operatively disposed to be in light bearing engagement with the fabric on the belt, means for adjusting the relative position of the belt and the axis of rotation 45 of the roller thereby to regulate the intensity of engagement between the roller and the fabric under treatment and a stipple modifying roller operatively disposed to modify the effect produced by the stippling 50 roller.

2. In a stippling machine, the combination with a belt adapted to carry the material to be stippled, three rollers disposed with their axis parallel and with their peripheral surfaces in bearing engagement with the belt, said rollers identified in order in the direction of travel of the belt as a color applying roller for applying a coating to the material, a stippling roller for stippling the color and a stipple modifying roller for smoothing out the stippled effect.

3. In a stippling machine, the combination with a belt adapted to carry the material to 65 be stippled, three rollers disposed with their

axis parallel and with their peripheral surfaces in bearing engagement with the belt, said rollers identified in order in the direction of travel of the belt as a color applying roller for applying a stippled coating to the 70 material, a stippling roller, and a stipple modifying roller for smoothing out the stippled effect and a single control for simultaneously modifying the position of all of 75 said rollers relative to the belt.

4. In a stippling machine, the combination with a belt adapted to carry the material to be stippled, three rollers disposed with their axis parallel and with their peripheral surfaces in bearing engagement with the belt, 80 said rollers identified in order in the direction of travel of the belt as a color applying roller for applying a stippled coating to the material, a stippling roller, a stipple modifying roller for smoothing out the stippled 85 effect, a single control for simultaneously modifying the position of all of said rollers relative to the belt and means for adjusting each roller relative to the belt and independently of the adjustment provided by said 90 single control.

5. In a stippling machine, the combination with a carrying belt, two idler rollers disposed with their axis parallel and with their peripheral surfaces in bearing engagement 95 with and rotated by the material to be stippled and carried by the belt, the surfaces of each of said rollers defined by a sponge-like flexible material.

6. In a stippling machine, the combination with a belt, of a pair of transversely spaced apart guiding frames, a bracket mounted in each frame for vertical movement, a plurality of stippling rollers, each mounted for rotary movement at opposite ends in said 100 brackets and adapted to have their peripheral surface engage material carried by the belt, and a manually actuated control for simultaneously adjusting the vertical position of both of said brackets thereby to adjust the rollers relative to the material carried by the belt.

7. In a stippling machine, the combination with a belt for carrying the material to be stippled, of a bracket guiding frame positioned to one side of the belt, a bracket slidably mounted for vertical movement on said frame, manually actuated means for adjusting the vertical position of the bracket, a saddle adjustably mounted in the bracket, 115 a cylinder shaft demountably journaled in said saddle, and a stippling roller carried by the shaft.

8. In a stippling machine, the combination with a belt for carrying the material to be stippled, of a bracket guiding frame positioned to one side of the belt, a bracket slidably mounted for vertical movement on said frame, a lifting cam for elevating the bracket, springs between the frame and 120

4
bracket for maintaining the bracket in engagement with the cam, a saddle mounted in the bracket, a cylinder shaft demountably journaled in said saddle, and a stippling roller carried by the shaft.

- 5 9. In a device for stippling fabrics, the combination of a travelling belt for feeding the fabric to be stippled, a cylindrical stippling roller, extending across the line of travel of the belt and provided with a sponge-like work face for engaging the fabric as it is fed past the same by the belt and means for adjusting the intensity of engagement between the roller and the fabric 10 whereby a relatively light contact may be maintained as the face of the roller wears away.
- 10 10. In a device for stippling fabric, the combination of a stippling roller having a sponge-like work face, and means for feeding a fabric across said roller in a plane tangent to its work face and in light bearing engagement with its sponge-like work face.
- 11 11. In a stippling machine, the combination of a carrying belt for carrying the material to be stippled, and a stippling roller having an irregular sponge-like work face containing irregular suction pockets for engaging the material on the belt.
- 12 12. In a stippling machine, the combina-

tion of two rollers, one of said rollers constituting a color applying means for coating the material to be stippled and the other roller having a sponge-like face for stippling the coated material and means for feeding the material past both of said rollers in a direction from the color applying roller towards and past the stippling roller.

13. In a stippling machine, the combination of two stippling rollers, each provided with a sponge-like work face, the face of one of the rollers being different from the face of the other roller whereby the stippled effect produced on the material under treatment by one of the rollers is modified by the action of the other roller.

14. In a stippling machine, the combination of two rollers, each provided with a work face formed of a soft sponge, one of said rollers constituting a color applying roller for coating the material to be stippled and the other roller constituting a means for stippling the coated material.

Signed at New York city, in the county of New York and State of New York, this 11th day of June, A. D. 1921.

CHARLES G. HAMPSON

Witness:

SARA A. THORNTON.
